UNITED STATES PATENT OFFICE.

EWALD E. STURK, OF DAVENPORT, IOWA.

TOY CANNON.

1,358,125.

Specification of Letters Patent.

Patented Nov. 9, 1920.

Application filed January 22, 1920. Serial No. 353,271.

To all whom it may concern:

Be it known that I, EWALD E. STURK, a citizen of the United States, residing at Davenport, in the county of Scott and State of Iowa, have invented certain new and useful Improvements in Toy Cannon, of which the following is a specification.

This invention relates to toy cannon and has for its primary object to provide a device of this character, similar in appearances to the ordinary cannon, whereby a large number of small spherical shaped projectiles may be ejected therefrom in quick succession.

Another object is to construct a novel toy cannon that will be perfectly harmless in its use and highly efficient in its operation; furthermore, one that will be simple in its construction, durable and wherein none of the parts are liable to break or become out of order.

Another object is to provide means whereby the barrel of the cannon may be elevated to different angles for throwing the projectile to different distances.

Another object of the invention is to provide a simple and efficient means for operating the device so that the projectile may be brought in alinement with the bore of the cannon's barrel and ejected therein and therethrough.

Other objects and the advantages thereof will appear in the detailed description below and in the accompanying drawings, 35 wherein—

Figure 1 is a vertical longitudinal section taken centrally through my invention.

Fig. 2 is a rear elevation of my invention, and

40 Figs. 3 and 4 are sections taken on lines 3—3 and 4—4 respectively of Fig. 1.

By referring to the accompanying drawings by numerals, it will be seen that 1, designates the barrel of the cannon having 45 the central bore 2 extending throughout its length, a front sight 3 and a rear sight 4 are mounted adjacent the extremities of the barrel in any suitable manner.

An arcuate stand 5 is provided with the 50 feet 6 and a stop 7 which is struck upwardly from the body of the stand. The bracket 8 is bent so as to form an upright portion and an arcuate portion will rest upon the stand 5 so as to be slidably mount-

ed thereon by means of the bands 9. The rear portion of the arcuate portion of the bracket 8 is provided with a pair of tongues 10 for a purpose to be hereinafter described.

A container 11 is fixedly attached to the upright portion of the bracket 8 in any suitable manner and is substantially heart shaped in cross section so as to provide the bottom channel 14 for receiving the bottom-most projectiles 12. A groove 13 is provided in the top portions of the container 11 for receiving the barrel 1 as is clearly shown in Figs. 1 and 4 of the drawing. The container 11 is provided with a rear open end which is closed by the rear bracket 15 which has an opening 16 adapted to register with the channel 14 so that the projectiles 12 may pass therethrough. A brace 17 is fixedly attached to the inner face of the bracket 15 by means of the rivet 18 and this brace is substantially U-shaped and provided with 75 an aperture for receiving the spindle 19 which passes also through the bracket 15. A cog wheel 20 is mounted upon the spindle 19 and is keyed thereto. This cog wheel 20 is provided with the teeth 21 so as to form 80 spaces 22 therebetween. It should also be noted that the teeth 21 are formed so as to space apart their ends, thereby making the openings larger at the periphery of the teeth 21. A disk 23 is also mounted upon 85 the spindle 19 and is attached to the cog wheel 20 in any suitable manner and is provided with peripheral openings 24 which are adapted to register with the openings 22 in the cog wheel 20. By referring especially to Fig. 2 of the drawing it will be seen that these openings 24 are substantially rectangular in shape and will therefor prevent the projectiles 12 which are situated in the opening 22 from falling out.

90 A drum 28 surrounds the wheel 20 and the disk 23 and is provided at its top portion with a notch shown in Figs. 1 and 2 of the drawing. A plurality of packing lips 25 are struck from the disk 23 and arranged 100 in a circle. A spring 32 is attached to the bracket 15 by means of a rivet and extends around the wheel 20 and the disk 23 so as to have the spindle 19 passed therethrough. The spring then extends upwardly so as to 105 form a spring hammer 33 the top of which will register with the uppermost opening 24. An operating lever 31 is pivotally mounted

upon the spindle 19 and is adapted to work within the slot provided in the guide 30 which is situated to one side of the drum 28.

By referring especially to Fig. 2 of the drawing it will be seen that when the lever 31 is raised to its uppermost position within the guide 30 it will engage one of the lips 25 after which the lever may be pushed downwardly thus causing one of the lips 25 to crack the hammer 33. By then pushing the lever 31 to its bottommost position in the guide way 30, the hammer 33 will be released and allowed to strike the projectile 12 situated in the uppermost opening 24 thereby forcing same into the barrel 2 with sufficient momentum so that same will pass therefrom.

The breech mechanism consisting of the bracket 15, the wheel 20, the disk 23, and the mechanism mounted thereon may all be detached from the remaining portions of the cannon and attached thereto as may be desired. By referring especially to Figs. 1 and 3 of the drawing it will be seen that a pin 40 is provided adapted to register with the aperture 41 provided in the bracket 15. This pin 40 is formed of resilient material and is carried upon the bottom of the container in any suitable manner. By having this pin 40 formed of resilient material, it will be seen that the tongues 10 may be passed through the apertures provided in the bracket 15 after which the pin 40 may be passed through the aperture 41 by bending same so as to register therewith. The pin then will have a tendency to extend in alignment with the sides of the container 11 thereby causing sufficient friction to hold the breech mechanism thereto. When the wheel 20 is rotated by means of the lever 31 in the manner described it will be seen that the projectile 12 will pass through the opening 16 in the bracket 15 so as to be positioned in one of the openings 22 and the wheel 20. When the wheel is then rotated it will be seen that the projectile 12 will be delivered successively to a registering position with the bore 2 and so as to be successively ejected therethrough by means of the spring hammer 33 which will be raised by the cocking lips 25. It will also be seen that the cocking lips 25 are so arranged that the hammer 33 will be in a raised position when the same is directly over the teeth 21 and because of the sudden termination of the lips which are struck from the disk 23, the hammer will be suddenly released and allowed to strike the projectile 12.

In order to throw the projectiles 12 to different distances it will be seen that the bracket 8 is slidably mounted upon the arculate stand 5 so that same may be moved thereon thereby elevating or depressing the barrel 1. A stop 7 is provided so that the barrel 5 will always be in an elevated posi-

tion so that the projectiles 12 will roll toward the opening 16.

Having thus described my invention it will be seen that I have produced a toy cannon which is constructed so as to resemble an ordinary cannon and will afford considerable amusement to young children and at the same time is perfectly harmless and that the parts thereof are not liable to become easily broken or to become out of order. It will also be seen that the device is capable of being cheaply and easily manufactured and therefore sold at a low cost upon the market.

Having thus described my invention what I claim as new is:—

1. In a toy cannon, a barrel having a bore extending therethrough, a container being substantially heart shape in cross section, said barrel being secured in the groove formed in the top thereof, and means for delivering the projectiles from said container to a position in alignment with the bore of said barrel.

2. A breech mechanism to be used with a device of the class described comprising a bracket having a brace thereon, a spindle passing through said bracket and brace, a cog wheel mounted upon said spindle and provided with a plurality of peripheral teeth so as to form openings therein, a disk mounted upon said spindle and fixedly attached to said wheel and provided with a plurality of peripheral openings adapted to register with the openings provided in said wheel, and means for rotating said disk.

3. In a toy cannon, a barrel having a bore extending therethrough, a container for receiving a plurality of projectiles and being substantially heart shape in cross section providing a groove at its top in which is secured said barrel, a bracket attached to said container, a wheel provided with a plurality of teeth, said wheel being mounted upon said bracket at the rear of the container and barrel, a disk fixedly attached to said wheel, means for rotating said disk and means for ejecting said projectiles into and out of the bore of said barrel.

4. In a toy cannon, a barrel having a bore therein, a container for receiving a plurality of projectiles, means for supporting said container and said barrel, a cog wheel for delivering said projectiles from said container to a position in alignment with the bore of said barrel, a disk fixedly attached to said wheel, a plurality of cocking lips arranged in a circle upon said disk, a spring hammer for engaging said cocking lips when the disk is rotated so that when said hammer is released it will eject said projectile into and out of the bore of said barrel, and means provided for manually rotating said disk.

5. A toy cannon comprising a barrel, hav-

ing a bore extending therethrough, a container upon which the barrel is mounted, means provided for supporting said container and said barrel, a cog wheel mounted upon said container and at the rear of said barrel, a disk fixedly attached to said wheel, a plurality of cocking lips arranged in a circle upon said disk, a spring hammer arranged behind said disk so that its free ex-

tremity will register with the bore of said barrel, and an operating lever for said wheel 10 and disk.

In testimony whereof I affix my signature in presence of two witnesses.

EWALD E. STURK.
